CLAIM

The ornamental design for beverage can lid, as shown and described.

DESCRIPTION

FIG. 1 is a left side elevational view of a beverage can lid showing my new design, the right side of which is a mirror image thereof;

FIG. 2 is a top plan view thereof;

FIG. 3 is a front elevational view thereof;

FIG. 4 is a rear elevational view thereof;

FIG. 5 is a bottom plan view thereof; and

FIG. 6 is a cross-sectional view taken along line 6—6 of FIG. 3.
